BEATING-UP LINE POSITION INDICATOR FOR LOOMS

Filed May 8, 1934

UNITED STATES PATENT OFFICE

2,001,061

BEATING-UP LINE POSITION INDICATOR
FOR LOOMS

Carroll H. Gibbs, Springfield, Mass.

Application May 8, 1934, Serial No. 724,553

6 Claims. (CL. 139—1)

This invention relates, in general terms, to loom equipment but deals more specifically with a device, mounted on the loom parts, by means of which the weaver or loom tender is enabled, 5 through manual actuation of the device, to accurately ascertain whether or not the beating-in operation has been properly performed.

In weaving operations, the web or finished portion of the fabric being manufactured sometimes 10 advances faster than the reed fully beats in the weft or filler threads. If this advance occurs suddenly, due to causes which will be later given consideration, one or more "picks" of the filler will be lost and a "run" will show in the finished 15 cloth. Or a difficulty which is more gradual in its development might occur, resulting in a somewhat too loosely woven fabric.

The web of cloth is wound on a drum and any 20 in formality in the winding operation might cause either one of these difficulties. Then there is a possibility that trouble might arise in the tensioning apparatus which maintains a strain on the warp threads. Variations in this strain will often cause uneven weaving, and variable positioning of the beating-up line of the reed, and to 25 remedy this trouble, or at least to locate it in a very simple and convenient manner I have conceived the present invention, by the use of which these particular troubles in weaving operations 30 may be anticipated and the remedy applied with less time consumed and effort expended than obtains with the conventional method of accomplishing these objects.

The device by means of which I attain the 35 objects set forth comprises a standard from which extends a bar overhanging the material being woven and an arm pivotally mounted to swing from the bar, together with an indicator element having longitudinal yieldability, disposed at the 40 free end of the arm. It also includes facilities for making various adjustments to bring the indicating element into proper relation with the beating-up line of the cloth and automatic means to maintain the indicator-equipped arm in a position in which, normally, it is out of conflict with 45 and removed from any and all moving parts of the loom.

The character of the invention may best be 50 understood by reference to the description found in the following specification when taken in connection with the accompanying drawing disclosing an embodiment which, at the present time, I consider preferable to other possible forms in which the invention might be carried out.

55 In the drawing—

Fig. 1 represents in more or less diagrammatical form portions of a loom with my device mounted thereon;

Figs. 2, 2a and 3 are plan views showing the application of the device with particular reference to the relation of the indicator with the beating-up line of the cloth;

Fig. 4 is a perspective view of the device;

Fig. 5 is a face view of the positioning block;

Fig. 6 is a central, longitudinal section of the 10 swinging arm;

Fig. 7 is a section on line 7—7, Fig. 6;

Fig. 8 is a section in plan view, taken on line 8—8, Fig. 7;

Fig. 9 is an end view of the rotating head;

Fig. 10 is a section taken on line 10—10, Fig. 7;

Fig. 11 illustrates a faulty weft-beating-in condition;

Fig. 12 is a section on line 12—12, Fig. 5;

Figs. 13 and 14 represent indicator elements 20 embellished in different colors; and

Fig. 15 is a plan view of the indicator bar parts.

Similar reference characters are employed to identify like parts in all the different views of 25 the drawing.

Referring to the drawing, W represents the warp threads, T the weft or filler threads, R the reed, S the shuttle, C the web of cloth, B the finished cloth wound on the drum, and H the 30 hand-wheel used to manually actuate the drum, all of which are conventional and usual equipment for looms.

In weaving, the reed R moves forwardly and backwardly, and on the forward movement, or 35 beat, forces the weft threads T along the warp threads to form the finished web of cloth, C.

At the end of each forward beat, immediately before which one "pick" of the filler is made across the lay of the loom, the front edge of the reed 40 stands on the line L, as shown in Fig. 2 in which the web of cloth is depicted as being fully and correctly beat-up by the reed.

But in Fig. 3, the line La, which represents the end of the web in which the filler material has 45 been fully beaten in, has advanced faster than the weft threads Ta have been shuttled across the lay and fall short of being fully beat up by the reed into the web of cloth, leaving intervening spaces which weavers call "runs" and which resemble and to all intents and purposes constitute dropped picks which would later appear as such in the finished fabric unless perchance, through the vigilance of the operator, they are detected in time to correct.

The conventional procedure taken by the weaver in correcting this trouble when it arises, is to first stop the loom and withdraw the filler threads T_a . Then by releasing the ratchet mechanism (not shown) on the winding drum, permit the usual tension which is maintained on the warp threads W to retract or pull back the finished and completely beat in web until the beating-up line of the cloth registers with the forward edge of the reed when the latter is advanced to its extreme forward position, as shown in full lines, Fig. 1.

But in performing this operation the whole feed mechanism of the loom must be manually actuated in order that the reed be accurately brought to this advanced position. This involves considerable time and effort on the part of the operator, and can be wholly obviated by the use of my device.

In Fig. 4 of the drawing I illustrate my beating-up-line indicator which comprises a standard 1 mounted on any accessible portion 2 of a loom. On the top of the standard a horizontal arm 3 carries a yoked portion 4 within the branches of which is an adjustably mounted block 5.

The block 5, as will be seen by reference to Fig. 12, has a groove 6 engaging which is a tongue 7 in the yoked portion of the arm 3. This construction holds the block normal to the arm at all times.

Extending through the branches $3a$ of the yoke is a thumb screw 8 having screw-threaded engagement with the block 5, and serving as means to re-position the block within the confines of the yoked portion 4. A graduated scale 9 assists in making accurate adjustments of the block, and after being made, the parts are rigidly held together by the cap screw 10. A slotted hole 11 permits transverse movement of the block over the screw 10.

Extending inwardly from the block 5 and disposed above and spaced from the web of the cloth C , is a bar 12 secured in the block by a threaded end 12a. The opposite end of the bar is reduced, as at 13, and on this reduced portion is fixed a mandrel 14 secured thereon against rotation by the key 15 and against endwise displacement therefrom by the set screw 16.

A sleeve 17, having a straight bore 18, is mounted for rotation on the mandrel 14, this movement being restricted to within the limits of the cut-away portion 19 and held therein by a set screw 20 (see Fig. 10).

To hold the sleeve from withdrawal off the mandrel a pin 21 is secured in the sleeve and passes into the circumferential groove 22 in the mandrel. To maintain the sleeve in its normally disposed position, as shown in full lines in Fig. 4, a torsional spring 24 is provided, one end thereof being fixed in the mandrel, at a , and the opposite end attached to the end of the screw 25 projecting through the wall of the sleeve.

Extending from and secured to one side of the sleeve by a threaded connection therewith at 26, is a tubular indicator arm 27 having a large bore 28, two bores 29 and 30, respectively, of substantially the same size, and a relatively small bore 31 disposed between the last two bores mentioned.

Within the indicator arm 27 is an indicator bar assembly shown in plan view in Fig. 15 and in part sectional elevation in Fig. 6.

On the inner end of the indicator bar is a thin angular lever 32, the short, offset portion 32a being pivotally secured, eccentrically, to the end

of the mandrel 14 by a screw 33. The opposite end of the member 32 is slidably disposed in the scarf 34 cut in the rod 35, and secured therein by a pin 36 which operates in the slotted hole 32b.

Extending forwardly from the portion 35 is a smaller diameter rod 37 the outer end of which has screw-threaded engagement with the stub-rod 38, which latter carries the V-shape indicator 39. The indicator is secured for end-wise adjustment in the scarf 38a in the stub-rod 38, by means of screws 40 operating in the slotted hole 39a in the indicator member. A key-pin 41 travelling in a key-way 42 in the end of the indicator arm 27 maintains parallelism of the flat indicator with the bar 12.

A compressible spring 43, disposed in the bore 30, thrusts on the shoulder 30a of the bore, and on the inner end of the stub-rod 38, normally holding the shouldered portion of the rod 35 against the shoulder 29a of the bore 29.

The torsional spring 24 tends to swing the indicator arm to, and hold it yieldingly in, the position marked "X" in Fig. 4; and as the pivot screw 33 is off the axial or swinging point of the arm, the movement of the latter above the horizontal will cause the indicator bar parts to recede a short distance into the tubular arm 27, the spring 43 compressing as the arm moves upwardly. The same action takes place when the arm is swung below the horizontal, but the movement in this case is not so pronounced, as can be seen by reference to Fig. 1.

The automatic receding of the indicator rod parts is provided for the purpose of preventing interference with other working parts of the loom when the indicator is swung upwardly. The compression spring 43 further serves to safeguard the parts should the indicator be lowered into engagement with the reed while the loom is operating.

The bar 12 may be re-positioned in any one of the screw-threaded holes 44 in the block 5, for roughly locating the indicator. The fine adjustments are made as will hereinafter be explained.

As it is essential that frequent tests be made with the indicator to determine whether the filler material is being properly beat into the cloth, I have provided an odometer 45 the shank 45a of which is secured on the reduced portion 13 of the bar 12. The odometer spindle 46 has a sector of a gear 47 fixed thereon, this gear meshing with the gear teeth 48 cut on the periphery of the sleeve 17. On each downward movement of the indicator arm the odometer registers one more figure, and in this manner account may be kept of the number of times the weaver has used it in his work. A cover 49 closes the outer end of the sleeve 17.

I have found it to be of great advantage while making tests with my indicator to ascertain the accuracy or inaccuracy of the beating-up line of the cloth, to paint, enamel or otherwise color the upper face of the indicator blade 39, the color to be one which contrasts with the color of the goods being manufactured. For instance, black on white, a deep red on a pale yellow, etc., bearing in mind that colors which are not too much in contrast might be more suitable than ones which were in extreme contrast. This matter may readily be ascertained by experimentation, the object being to provide combinations which react on the optic nerve to the best advantage.

In installing one of my devices on a loom the latter is operated until a short piece of the

finished web of cloth is woven and the preliminary beating-up line of the cloth accurately established. This preliminary line coincides with the front face of the reed when positioned at the extreme forward end of its beat movement. The indicator parts must now be adjusted so that when the arm is swung downwardly the end of the indicator plate 39 comes into close contact with the reed.

10 The positioning of the parts may involve shifting the bar 12 into another of the tapped holes 44, and it may include lengthening or shortening the arm by the withdrawal of the shank of the indicator blade 39 slightly out of, or inserting it further into, the scarf 38a by relaxing the screws 40 which clamp the shank in the split end of the stub-rod 38. In any event the free end of the indicator should closely contact the reed in this preliminary adjustment operation.

20 But the position of the front face of the reed does not indicate the true beating-up line of the cloth, due to the fact that after withdrawal of the reed into its rearward position the cloth slightly expands in a direction toward the reed, and it is on this expansion line of the web of the cloth that the forward or free end of the indicator blade must register when making tests.

It is, therefore, necessary to make a final adjustment of the indicator element while the reed is withdrawn from the beating-up line.

30 This is accomplished by actuation of the thumb screw 8, made after relaxing the cap screw 10, the movement being checked by the graduations 9, each of which constitutes or represents one pick of the filler material.

35 It might be well to explain, at this point, that the expansion of the fabric, rearwardly of the preliminary beating-up line will vary with different grades of material being woven, but usually it will require two picks, and sometimes more of rearward adjustment of the indicator to compensate for the expansion movement of the cloth, toward the reed, after the withdrawal of the latter from its extreme forward position.

40 After this final adjustment is made, the indicator automatically swings upwardly into the position in which it is shown in full lines, Fig. 4, and thereafter, when a test is to be made, the loom is stopped, with the reed in its backward position. 45 Should the indicator register with the beating-up line in any testing operation, it is proof that the fabric is being woven properly, but if not it indicates that something is wrong.

50 Should conditions appear as shown in Fig. 3, the remedy is to stop the loom, with the reed positioned as shown in dot and dash lines, and release the ratchet mechanism on the winding drum, permitting the tensioning strain on the warp threads to draw the web back to the true beating-up line which, in this instance, is coincident with the end of the indicator blade 39, the filler threads Ta being in some cases pulled out of the web and in others left intact to be beat in by the reed, the weaver using his judgment as to the number of loosely woven filler threads the reed is capable of properly beating-up when "runs" like that shown in Fig. 3 appear.

55 The fact that, in operation, my indicator requires practically no effort on the part of the weaver to actuate leaves but slight excuse for producing inferior goods. The weight of his hand will swing the indicator down on to the web of cloth and it automatically rises through the agency of the spring 24. The operation con-

5 sumes but a few seconds of time, gives accurate indication of the character of the beating-up process and facilitates the work of correcting faults in the weaving which present-day methods do not contemplate.

5 Moreover the weaver can easily attend more looms, is enabled to produce a better grade of goods and takes more interest in his work for the reason that it is less irksome. The practicability and effectiveness of my indicator will, it is believed, commend itself to those interested in loom operations.

10 What I claim is:

15 1. A beating-up line indicator for looms comprising a standard adapted to be secured on a stationary portion of the loom, a bar extending from said standard, over the web of cloth, a sleeve mounted for restricted rotation on the end of said bar, an indicator arm mounted on and swinging with said sleeve, the end of said arm adapted to contact the top of the cloth and swing in a plane disposed normal to the weft thread thereof, a spring disposed between said bar and said sleeve adapted to automatically return said indicator arm to its original position after being 20 manually depressed and the manual pressure released and means to variously position said bar on said standard for the purpose of bringing the free end of said indicator arm into register with the weft-beating-up line of the cloth.

25 30 2. A beating-up-line, position indicator for looms, comprising a standard, a bar extending from said standard over the portion of cloth last beaten up, a mandrel on the end of said bar, a sleeve revolvably mounted on said mandrel, a spring yieldingly holding said sleeve in a predetermined position circumferentially of and with respect to said mandrel, a tubular indicator arm secured on and disposed normal to said sleeve, an indicator rod in said indicator arm, and a 35 colored indicator plate element on the outer end of the indicator rod, said plate being of a color contrasting with that of the shade of goods being woven.

35 40 45 50 55 3. A beating-up-line indicating device for looms comprising a standard, a bar extending from said standard, a mandrel secured on said bar, a sleeve mounted for restricted rotary movement on said mandrel, a tubular arm secured in the side of said sleeve, an indicator rod assembly in said tubular arm, one end thereof being eccentrically pivoted to said mandrel, and a colored indicator plate element on the outer end of said indicator rod assembly, said element adapted to yield longitudinally of and relative to said tubular arm.

4. A beating-up-line indicating device for looms comprising a standard, a bifurcated arm extending horizontally from said standard, a block disposed on said arm, between the branches of the bifurcated portion thereof, means to variously position said block within said bifurcated portion, a bar secured to and extending outwardly from said block, a mandrel on the outer end of said bar, a sleeve rotatable on said mandrel and held thereon against end-wise displacement therefrom, an indicator arm mounted on and adapted to swing with said sleeve, and an end-wise yieldable indicator element on the outer end of said indicator arm adapted, when depressed, to register with the last pick of filler material which has been correctly beat into the cloth being woven.

5. A beating-up-line indicating device for looms comprising a bar disposed over and spaced

from the web of cloth being woven, a mandrel on the end of said bar having a reduced portion on its circumference, a torsional spring disposed in said reduced portion, one end of said spring being secured to said mandrel, a sleeve rotatable on said mandrel, the opposite end of said spring being secured in said sleeve, whereby said sleeve rotates in response to the action of said spring in one direction, a tubular indicator arm secured on and disposed normal to said sleeve, an indicator rod disposed within said tubular indicator arm and eccentrically connected at one end to said mandrel, whereby in rotating said sleeve reciprocal movement is given said rod in and

relative to said tubular indicator arm, gear teeth on said sleeve, a segmental gear engaging the teeth on said sleeve, whereby a rotary movement is given said segmental gear when said sleeve is rotated, and means associated with said segmental gear for recording alternate oscillatory movements of said tubular indicator arm. 5

6. A beating-up-line indicating device for looms, having characteristics according to claim 5, and a stop pin adapted to limit the rotary movement of said sleeve when said tubular indicator arm has automatically swung upwardly and reached a predetermined angle of inclination. 10

CARROLL H. GIBBS.
